UNITED STATES PATENT OFFICE.

FREDERICK E. HEINIG, OF LOUISVILLE, KENTUCKY.

TAG FOR TOBACCO.

SPECIFICATION forming part of Letters Patent No. 249,351, dated November 8, 1881.
Application filed August 20, 1881. (No model.)

To all whom it may concern:

Be it known that I, FREDERICK E. HEINIG, of Louisville, Kentucky, have invented a new and useful Improvement in Tags for Tobacco, 5 of which the following is a clear, full, and exact description, reference being had to the accompanying drawings, making a part of this specification, in which—

Figure 1 is a perspective view of my improved tag. Fig. 2 is a view of a blank from which the tag is formed.

The object of my invention is to produce an attractive and cheap tobacco-tag which may present to the eye different colors; and it consists in folding the material used for the tag so as to present portions of each side of its different-colored faces at the same time.

To enable others skilled in the art to make and use my invention, I will proceed to describe 20 the exact manner in which I have carried it out.

In the drawings, A represents the blank from which I form my folded tag, and B represents

the tag complete. The blank A has its faces of different colors, *a b*, and when folded, as 25 shown at B, both colors are displayed at the same time. The pointed ends *c* of the tag are bent down to form the fasteners. This makes an exceedingly attractive tag and one that can be manufactured at trifling expense. 30

I do not confine myself to any particular design for the tag, as this may be greatly varied without departing from the spirit of my invention.

Having thus explained my invention, what 35 I claim as new, and desire to secure by Letters Patent, is—

As an improved article of manufacture, a tobacco-tag having different-colored faces and folded so as to show both colors at the same 40 time, substantially as set forth.

FREDERICK E. HEINIG.
